TYPEWRITING MACHINE

Henry Joseph Hart, West Hartford, Conn., assignor to Royal Typewriter Company, Inc., New York, N. Y., a corporation of New York

Application April 4, 1934, Serial No. 719,015

9 Claims. (Cl. 197—183)

The invention relates to new and useful improvements in typewriting machines generally although more particularly to means engageable by the type bars in the course of their travel 5 toward the platen and effective to retard the speed of movement of said bars and thereby reduce to the minimum noise occasioned by the striking function of said bars.

An object of the invention is to provide a 10 yieldable contact member mounted in position to have a portion thereof engaged and bodily displaced by a type bar just prior to its striking the platen for retarding the speed of movement of said type bar and reducing to a minimum the 15 noise occasioned by its impact with the platen.

In its more detailed nature the invention resides in the provision of a coil spring buffer unit 20 secured at its ends only to the type bar segment and having its intermediate portion disposed in the path of travel of the type bars in a manner 25 permitting the same to be yieldably displaced by impact of the type bars in moving toward the platen for the purpose of slowing up the movement of the type bars and minimizing noise of impact thereof with the platen, the displacement of the buffer unit portion being permitted by slight longitudinal extension of the unit as a 30 whole.

Another object of the invention is to provide a 35 novel arcuate deep groove mounting for the buffer unit enabling yieldable displacement of intermediate portions thereof and longitudinal extension of the unit as a whole upon striking contact thereof by the respective type bars.

In the drawing:—

Figure 1 is a fragmentary face view illustrating the invention applied to a type bar segment.

Figure 2 is an enlarged vertical cross section taken on the line 2—2 on Figure 1.

Figure 3 is an enlarged detail sectional view 40 illustrating the displacement of a buffer portion upon type bar impact, the displaced position being shown in dotted lines.

Figure 4 is an enlarged detail section illustrating one end mounting of the buffer unit.

In the drawing, 5 designates the usual type bar support or segment which is equipped with a plurality of variously spaced radial kerfs or slots 6 to accommodate the mounting and movement of the usual type bars 7. As is customary in the art, the type bars are pivoted to the segment 5 as indicated at 8 and equipped with the usual type blocks 9. The usual center guide for the type bars is indicated at 10.

The type bar support or segment 5 is of the

usual arcuate shape, the collection of type bar pivots being disposed in an arc of a circle as will be observed by reference to Figure 1 of the drawing. The segment includes the usual banking ring portion 11 which is concentrically disposed within the arc of the type bar pivots. In conventional typewriter structures the type bars strike the banking ring just prior to engagement of the type blocks 9 with the platen 21. The metal to metal contact of the type bars and the 10 banking ring and the high speed impact of the type blocks 9 with the platen result in objectionable noise which the present invention seeks to reduce to a minimum.

In the practical development of the invention, 15 the front face of the segment 5 is equipped with a V-shaped groove 12 disposed concentrically between the banking ring portion 11 and the arc of the type bar pivots 8. While I have specified that the grooveway 12 is V-shaped, the specific 20 shape of said grooveway is immaterial so long as the upper wall 13 thereof extends downwardly and rearwardly from the front face of the segment as illustrated in Figures 2 and 3 of the drawing. The upper or foremost portion of the wall 13 25 merges with an overhanging retainer lip 14, the purpose of which will soon become apparent.

The grooveway 12 extends through the upper 30 edge of the segment 5 as illustrated in Figure 1 of the drawing and at each terminus of the grooveway is mounted a bracket member 15, said bracket members being secured as at 16 to the segment. A close-coiled spring buffer 17 is mounted in and conforms to the arcuate shape 35 of the grooveway 12 and is screw secured at its ends as at 18 to the bracket members 15. Secured at its ends alone the spring buffer unit 17 is normally held against the retaining lip 14 with the forwardly presented portions of the coils thereof projecting just slightly beyond the banking ring portion 11 as indicated at 19 in Figures 2 and 3 of the drawing.

Positioned as shown and described, the portions of the buffer spring unit 17 intermediate its end mountings 18 are disposed in the path of travel of the respective type bars toward the platen and because of the resiliency of the spring and its quality of permitting elongation intermediate of its fixedly secured ends the intermediate portions of said unit are free to yield to impact of said type bars. As each type bar is moved toward platen impact it first engages the buffer spring unit 17 and has its speed of movement retarded thereby for the purpose of reducing to a minimum the noise occasioned by type 45 50 55

bar, type block impact. The portion of the buffer spring unit 17 engaged by a particular type bar is bodily displaced thereby and caused to move down the grooveway wall 13 as indicated in dotted lines in Figure 3 of the drawing. Because of the relation of the rigid end ring mountings of the unit and the downwardly and rearwardly sloping wall 13, the displacement of the unit portion is attended by an elongation or stretching of the unit as a whole which serves to absorb the shock of impact of the type bar and also to materially reduce the speed of movement of said type bar.

After contact with the spring buffer unit 17 the type bars, having had the speed of their movement materially reduced, strike the banking ring portion 11 and thereafter, in the usual manner, the type blocks 9 engage the platen. Thus it will be seen that by engagement of the type bars with the yieldable, bodily displaceable spring unit portions, noise of impact of the type bars with the banking ring portion and also that of the type blocks 9 with the platen are reduced to a minimum. After each displacement of a buffer unit portion by type bar contact and the resultant elongation of the unit occasioned thereby by the displaced portion naturally springs back to normal position with the result that the type bar, after completing its impact with the platen, is speeded on its return to normal position. If desired a retaining pin or lug 20 may be positioned at the lower portion of the spring unit receiving grooveway 12 to prevent inadvertent displacement of said unit out of its receiving groove.

35 I claim:—

1. In a typewriter, the combination of a platen, a set of type bars movable into engagement with the platen, and a yieldable element supported in the path of movement of the type bars toward the platen and capable of slight elongation whereby intermediate portions thereof are bodily displaced upon impact thereof by said type bars for retarding the speed of movement of said type bars.

40 2. In a typewriter, the combination of a platen, a set of type bars movable into engagement with the platen, and an elongated buffer unit secured at its ends only and having a coiled spring body portion located in the path of movement of the type bars toward the platen whereby intermediate portions of said unit are free to yield bodily to type bar engagement.

45 3. In a typewriter, the combination of a platen, a set of type bars movable into engagement with the platen, a coiled spring buffer unit secured at its ends only and located in the path of movement of the type bars toward the platen whereby intermediate portions of said unit are free to yield bodily to type bar engagement, and means providing a grooveway to receive said unit and including a wall portion cooperating with the end mountings of said unit to cause the unit to be slightly elongated when a portion thereof is bodily displaced.

50 4. In a typewriter, the combination of a platen, a set of type bars pivotally supported with their pivots collectively disposed in an arc of a circle, and a yieldable element disposed in the form of an arc in the path of movement of the type bars toward the platen and capable of slight elonga-

tion whereby intermediate portions thereof are bodily displaced upon impact thereof by said type bars for retarding the speed of movement of said type bars.

5 5. In a typewriter, the combination of a platen, a set of type bars pivotally supported with their pivots collectively disposed in an arc of a circle, and an elongated buffer unit having a coiled spring body portion disposed in an arc of a circle in the path of movement of the type bars toward the platen and secured at its ends only whereby intermediate portions of said unit are free to yield bodily to type bar engagements.

10 6. In a typewriter, the combination of a platen, a set of type bars pivotally supported with their pivots collectively disposed in an arc of a circle, a coiled spring buffer unit disposed in an arc of a circle in the path of movement of the type bars toward the platen and secured at its ends only whereby intermediate portions of said unit are free to yield bodily to type bar engagements, and means providing a grooveway to receive said unit and including a wall portion cooperating with the end mountings of said unit to cause the unit to be slightly elongated when a portion thereof is bodily displaced.

15 7. In a typewriter, the combination of a platen, a set of type bars movable into engagement with the platen, a coiled spring buffer unit secured at its ends only and located in the path of movement of the type bars toward the platen whereby intermediate portions of said unit are free to yield bodily to type bar engagement, and means providing a V-shaped grooveway including an overhanging lip against which the unit normally rests and a wall portion over which portions of said unit are forced when yielding to type bar impact and which is shaped to cooperate with the unit end mountings to cause the unit to be slightly elongated while yielding bodily to type bar impacts.

20 8. In a typewriter, the combination of a platen, a set of type bars pivotally supported with their pivots collectively disposed in an arc of a circle, a coiled spring buffer unit disposed substantially 45 concentrically within the arc of type bar pivots and in the path of movement of the type bars toward the platen and secured at its ends only whereby intermediate portions of said unit are free to yield bodily to type bar engagements, and means providing a V-shaped grooveway including an overhanging lip against which the unit normally rests and a wall portion over which portions of said unit are forced when yielding to type bar impact and which is shaped to 50 cooperate with the unit end mountings to cause the unit to be slightly elongated while yielding bodily to type bar impacts.

25 9. In a typewriter, the combination of a platen, a set of type bars movable into engagement with the platen, a yieldable element supported in the path of movement of the type bars toward the platen and capable of slight elongation, supports for the ends of said element, and means providing a grooveway to receive said element and including a wall portion cooperating with the end supports of said element to cause the element to be slightly elongated when a portion thereof is bodily displaced.
